[57] CLAIM

I claim the ornamental design for a low profile universal scope mount set, as shown and described.

DESCRIPTION

FIG. 1 is a perspective view of a low profile universal scope mount set showing my new design.

FIG. 2 is a front elevational view thereof; the rear elevational view being a mirror image of the front.

FIG. 3 is a left side elevational view thereof.

FIG. 4 is a right side elevational view thereof.

FIG. 5 is a bottom plan view thereof; and,

FIG. 6 is a top plan view thereof.
